VACUUM CLEANER NOZZLE WITH REMOVABLE BRUSH ATTACHMENT

Filed Dec. 11, 1946

Fig. 1.

UNITED STATES PATENT OFFICE

2,659,924

VACUUM CLEANER NOZZLE WITH REMOVABLE BRUSH ATTACHMENT

Axel Albert Forsberg, Stockholm, Sweden, assignor to Aktiebolaget Elektrolux, Stockholm, Sweden, a corporation of Sweden

Application December 11, 1946, Serial No. 715,567

Claims priority, application Sweden
December 15, 1945

1 Claim. (Cl. 15—395)

1

This invention relates to nozzles for vacuum cleaners and more particularly to nozzles having a narrow elongated body intended for cleaning objects having narrow openings or corners. Such nozzles are frequently formed as an elongated flattened tube with or without a brush mounted in the mouth thereof.

In prior constructions of such nozzles a brush member rigidly connected with a holder consisting of metal guide members intended for insertion into the tube has been provided with apertures or the like adapted to receive screws passing through the tube wall from the outside to retain the brush member in position. Such a construction is disadvantageous in that the brush cannot be removed without the use of tools so that the nozzle is not immediately applicable for use with or without the brush mounted thereon. Moreover, the guide members disposed within the tube set up a comparatively high resistance to air flow.

A further known construction has included a brush member formed with a tubular metal shank into which the tubular member of the nozzle is inserted. In this construction the tubular form of the holder increases the width of the nozzle and prevents the nozzle being utilized for cleaning the same size gaps or narrow spaces with and without the brush.

One object of this invention is to provide a vacuum cleaner nozzle having a removable brush member which is simple and cheap to produce. A further object of the invention is to provide a brush member intended to be applied to and removed from a nozzle in a ready manner without the use of tools.

According to the present invention a brush intended to be readily replaceably mounted on a vacuum cleaner nozzle includes securing means in the form of a resilient stirrup serving as a support for the brush element and having its two ends relatively resiliently biased for engagement with recesses, apertures or the like formed in the wall of the nozzle body for holding said stirrup on the body.

More specifically, according to the invention, the brush includes a resilient stirrup carrying the brush element and having its two ends resiliently biased to engage with recesses, openings or the like of the nozzle body and to maintain such stirrup in position by said resilient biasing, the stirrup having one or more re-entrant portions adapted to cooperate with the nozzle body to prevent lateral displacement of the stirrup.

The invention also includes a vacuum cleaner

2

nozzle including a removable brush element mounted adjacent the nozzle mouth which comprises a nozzle body of flattened hollow form having its walls formed with recesses, apertures or the like, and a resilient stirrup carrying the brush element having its ends biased resiliently to engage with the apertures or the like, the nozzle body and the stirrup having co-operating portions which are relatively re-entrant and act to prevent lateral displacement of the stirrup relatively to said body.

The invention will be hereinafter more fully described with reference to the accompanying drawings showing one embodiment by way of example. In the drawings

Fig. 1 shows a side elevation, partly in section, of one form of nozzle fitted with a brush according to the invention;

Fig. 2 shows the brush by itself, also in side elevation; and

Fig. 3 is a sectional view taken on line III—III of Fig. 1.

Referring to Fig. 1, 10 designates a nozzle body consisting of metal, synthetic resin or similar material, which, as shown, has a flattened tubular head 11 and a round tubular shank 12 to which a hose of the vacuum cleaner is adapted to be connected. The opposite end 13 of the nozzle body forming the mouth is for practical reasons cut at an angle of about 45° to the longitudinal axis of the tube.

The brush element comprises a stirrup 14 which is preferably made of spring wire and forms a holder for the brush 15. The two limbs 16 of the stirrup, which on application to the nozzle are disposed adjacent the short curved sides of the nozzle body, are at their ends bent out to form eyes 17, the ends 18 of which are resiliently biased to project into two openings 19 formed in the wall of the nozzle and thus retain the brush on the nozzle body.

In order to provide lateral guidance of the stirrup relative to the nozzle body, its central portion 20 is bent in re-entrant shape in such manner as to encircle the edge of the nozzle mouth and also to project some distance into the mouth. The stirrup preferably bears resiliently against the edge of the mouth and/or against the curved sides of the nozzle.

The eyes 17 serve as handles for applying the brush to the nozzle when it is desired to clean the slots of a heating element, such as a radiator, for example; and for removing the brush when it is desired to clean with the nozzle member only as when cleaning the corners of upholstered

furniture, such as easy-chairs and the like, for example. The brush element 15 includes bristles which are secured in a well known manner by a twisted wire core which comprises woven strands of wire having its two end portions 21 clamped in two U-shaped sleeves 22 which are preferably welded to the stirrup 14.

It will now be understood that the cross-sectional area of the stirrup member 14 is relatively small compared to its length and the limbs 16 thereof are under tension and spring pressed toward one another to cause the ends 18 of the limbs to be firmly held in the recesses 19 when the stirrup member is mounted on the head 11 of the nozzle body 10. In such mounted position, the limbs 16 overlie the exterior surfaces of the narrow end walls in a direction lengthwise of the flattened nozzle head 11.

Further, the transverse connecting part 20 and portions of the limbs projecting beyond the narrow elongated opening 13 are disposed in a space defined by imaginary spaced apart planes flush with the exterior surfaces of the longer flat sides of the flattened head 11. The brush element at the vicinity of the narrow elongated opening, which is secured to the spaced apart limbs 16 of the stirrup member, includes bristles that normally extend a substantial distance beyond the imaginary spaced apart planes flush with the exterior surfaces of the longer flat sides of the nozzle head 11 from a region therebetween.

The above-described embodiment is given only as an example of the invention and may be modified in its details.

What is claimed is:

The combination with a suction nozzle having a flattened hollow body formed with spaced apart side walls and substantially smaller end walls terminating in a relatively narrow elongated opening, such end walls having recesses, of an attachment comprising a resilient stirrup member having spaced apart limbs and a part transverse to the limbs and connected thereto, the recesses in the end walls receiving the ends of the limbs and a portion of an intermediate region of the resilient stirrup member entering the elongated narrow opening of the nozzle when the stirrup member is detachably mounted on the nozzle body, such intermediate portion be-

ing formed so that the nozzle walls serve as a guide therefor, said resilient stirrup member having a relatively small cross-sectional area relative to its length and the limbs thereof being under tension and spring pressed toward one another to cause the ends of the limbs to be firmly held in the recesses when the stirrup member is mounted on the nozzle body and the limbs overlie the exterior surfaces of the narrow end walls in a direction lengthwise of the nozzle body, at least the transverse connecting part and portions of the limbs projecting beyond the narrow elongated opening being disposed in a space defined by imaginary spaced apart planes flush with the exterior surfaces of the longer flat sides of the nozzle body, and a brush element at the vicinity of the narrow elongated opening which is secured to the spaced apart limbs of the stirrup member and includes bristles that normally extend a substantial distance beyond the imaginary spaced apart planes flush with the exterior surfaces of the longer flat sides of the nozzle body from a region therebetween.

AXEL ALBERT FORSBERG.
